Primary Examiner — Jennifer L Watkins*Assistant Examiner* — Samantha Lynne Brodowski(74) Attorney, Agent, or Firm — Laura M. King; Matrix Law Group, LLP(57) CLAIM

The ornamental design for a combined wallet and card holder, as shown and described.

DESCRIPTION

FIG. 1 is a perspective view of the claimed design;

FIG. 2 is a front elevational view thereof;

FIG. 3 is a rear plan view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines are for the purposes of illustrating portions of the combined wallet and card holder and form no part of the claimed design.

1 Claim, 5 Drawing Sheets(56)
